UNITED STATES PATENT OFFICE.

JOSEPH E. EDWARDS, OF MEMPHIS, TENNESSEE.

DREDGE BUCKET.

Application filed April 11, 1922. Serial No. 551,591.

To all whom it may concern:

Be it known that I, JOSEPH E. EDWARDS, a citizen of the United States, residing at Memphis, in the county of Shelby and State of Tennessee, have invented certain new and useful Improvements in Dredge Buckets, of which the following is a specification.

My said invention relates to a dredge bucket and it is an object thereof to provide 10 a device of the character described which shall be more efficient in use than those at present known. A defect of the buckets now used is that the dirt becomes packed and adheres to the bucket instead of being dumped in proper manner. This is particularly true in dry land dredges, where the lubricating effect of water is lacking. There appears to be also a certain amount of suction in such dredges which helps to hold the 15 earth to the bucket and this is overcome in the operation of my device.

Referring to the accompanying drawings which are made a part hereof and on which similar reference characters indicate similar 20 parts,

Figure 1 is an elevation of the bucket and related devices viewed from one side,

Figure 2 an enlarged side view of the bucket,

Figure 3 a plan of the bucket frame, and Figure 4, a detail elevation of the trip.

In the drawings reference character 10 indicates the forked end of a dipper stick carrying the bucket which is the subject of my 35 invention and comprises a shell 11 and a bifurcated frame 12 having downwardly bent ears 13 and downwardly extending flanges 14. Both the ears and the flanges are perforated to receive a pivot 15 by which the bucket is swingably supported at the end of the dipper stick.

The bail of the bucket is shown at 16 and braces 17 are connected at one end to the upper end of the bail and at the other 45 to a pin 19 passing through ears 20 on the forks of the dipper stick. A link 18 at the upper end of the bail connects the bucket to a loading line 21 which passes over a pulley 22 on a boom 23, all in the usual manner.

The pin 19 forms also a pivotal support 50 for a trip 24. The trip 24 has at 25 an opening through which the rear end 12' of the bucket frame extends and at the upper end of the opening it carries an anti-friction roller 26 engaging said rear end. A line 27

is attached to the trip normally in the position shown in Figure 1. The trip line 27 passes about a roller 28 on the pivot 15, thence about a roller 29 on a rod 30 fixed to the forks 10 and so to the hole 31 at the upper end of the trip. The bucket is re-set by means of a re-setting or backing line 32 attached about midway of the pivot 15 and the end of the bucket at 12', this line passing over a roller 33 on a rod 34 also fixed in the forks 10. The trip is counterweighted at 36 to hold it in position.

It will be seen that the body of the bucket is shell-shaped and slopes equally or nearly so, toward either end from the middle, 70 whereas other buckets of which I am aware are flat at the bottom and have a rear wall substantially at right angles to the bottom. By my structure it will be seen that as the steel cutting edge 35 digs into the soil the earth taken up will pass smoothly along the bottom of the bucket without being packed at one place more than at the others. This is especially desirable in dry earth work and has been found satisfactory in heavy waxy 75 soil where other buckets would clog constantly. The pull on the load line and the force exerted by the conventional crowding boom attached to the dipper stick are effective along a line extending substantially 80 from pivot 15 to the cutting edge 35, producing a most effective cutting action, due in part to the rigidity of braces 17.

It will be seen also that the bucket of my device turns completely upside down which 90 assists in clearing the same of earth, partly because of the position assumed and partly because of the distance through which it swings whereby centrifugal force is brought into action to free the bucket of the material carried thereby. However, if the earth does not adhere to the bucket the upsetting of the bucket can be limited by means of the backing line. After it has turned over, the backing line will be pulled on the reverse swing of the bucket to return it to working position. As it swings back the end 12' strikes the weighted part of the trip to tilt the same. As both lines 32 and 27 are slackened the trip catches over the end 12' and holds the bucket in place. It will be noted that the line 32 is ordinarily slack to permit a pull on 27 to release the trip. Another advantage of the device is that stumps 95 do not become fixed to the bucket as in those 100 105 110 115

of ordinary type where it frequently becomes necessary to chop the stumps out with an axe.

If the bucket is not filled at the first forward stroke it is entirely safe to make a second stroke as there is no danger of accidental tripping of the bucket.

The maximum average daily yardage for dredge buckets now in use is about 15,000 10 cubic yards. With my improved buckets this is increased to a maximum of from 35,000 to 40,000 cubic yards.

Having thus fully described my said invention, what I claim as new and desire to 15 secure by Letters Patent, is:

1. In a dredge, a dipper stick, a bucket pivoted thereon having a shell-shaped bottom, a pivot slightly in rear of the bottom and underneath the bucket whereby the same 20 will be completely inverted under the action of gravity, substantially as set forth.

2. In a dredge, a dipper stick, a bucket pivotally supported thereby, a bail at the end of the dipper stick, a trip at the rear 25 of the bucket, a pivot for said trip and a brace for the bail attached to the dipper stick by said pivot, substantially as set forth.

3. In a dipper dredge, a dipper stick, a bucket pivotally supported at the front end 30 thereof, said pivot being slightly in the rear of the bottom and underneath the bucket, said bucket curving equally from its bottom point toward the front and rear ends, substantially as set forth.

35 4. In a dipper dredge, a dipper stick, a bucket comprising a shell curving substantially equally from the bottom toward the pivot end, a frame carrying said shell and providing downwardly extending flanges 40 and a pivot for the bucket extending through the dipper stick and said flanges, substantially as set forth.

45 5. A dipper dredge bucket having a shell curving substantially equally from the bottom toward the front and rear ends, a bifurcated frame supporting the same, said frame having downwardly extended longitudinal flanges and a rearward extension adapted to be acted on by a trip, substantially as set forth.

50 6. A dipper dredge comprising a dipper stick, a bucket having a shell and a flanged supporting frame therefor, a link at the forward end of said dipper stick and a pivot 55 passing through the dipper stick, the link and the flanges on the bucket, substantially as set forth.

60 7. A bucket dredge comprising, a boom, a forked dipper stick, a bucket pivoted between the forks of the dipper stick, a bail on the dipper stick, a brace rigidly connecting the upper end of the bail with the dipper stick and located substantially in alinement

with the loading line extending from the end of the boom to the upper end of the bail, 65 substantially as set forth.

8. A dipper dredge comprising a dipper stick, a bucket pivoted at the lower end thereof and having a rearward extension, a trip pivotally mounted adjacent the rear 70 extension and having a portion adapted to engage over the same, a trip line secured to the upper end of the trip, a pulley on the dipper stick in rear of the trip, a pulley on the pivot of the bucket and a trip line attached to the upper end of the trip and extending rearwardly over the first pulley, thence forward over the second and then rearwardly to an operator, substantially as 75 set forth.

9. A dipper dredge comprising a forked dipper stick, a bucket pivoted at the forward end of the same and having a rearward extension, a trip pivotally adjacent said extension and adapted to engage over the same, 80 a series of pulleys arranged between the forks of the dipper stick, a trip line extending from the trip back over the rear-most pulley, thence over the foremost pulley and to an operator, and a normally slack backing line for the bucket attached to one end of the trip line and extending from an intermediate pulley to its point of connection with the bucket, substantially as set forth.

95 10. A dipper dredge comprising a dipper stick, a bucket pivoted thereon and provided with a forward cutting edge, an upwardly extending bail a pair of braces secured to the dipper stick and extending to the bail, said braces being substantially parallel with the forward cutting edge of the bucket, and means for applying power through the braces to the dipper stick along a line passing through the pivot of the bucket and the forward cutting edge thereof, substantially as set forth.

11. A dipper dredge comprising a dipper stick, a bucket pivoted thereon at its forward end, said pivot being located rearwardly of the center of gravity of the bucket, an upwardly inclined rearward extension on the bucket, a pivoted trip having an opening surrounding said rearward extension and engaging the inclined upper surface thereof whereby the weight of the bucket holds the trip in place, substantially as set forth.

115 In witness whereof, I have hereunto set my hand and seal at Memphis, Tennessee, this 10th day of February, A. D. nineteen hundred and twenty-two.

JOSEPH E. EDWARDS. [L. S.]
